R. L. SHANNON

MAIL BAG LOCK

Filed Dec. 15, 1924

INVENTOR
R.L. SHANNON
BY *Munn & Co.*

ATTORNEYS

UNITED STATES PATENT OFFICE.

ROBERT LOWE SHANNON, OF CHICAGO, ILLINOIS.

MAIL-BAG LOCK.

Application filed December 15, 1924. Serial No. 756,032.

My invention relates to improvements in mail bag locks over that form of the device shown in my co-pending application for patent Serial No. 703,195, filed March 31, 1924. In said co-pending application I showed novel means for permitting the ropes of a mail bag to be moved through the lock in one direction so as to close the mouth of the mail bag and, at the same time, for preventing the movement of the ropes in a reverse direction until the lock was first unfastened by means of a key, whereby only authorized parties having possession of the requisite key could open the mail bag.

The principal object of the present invention is to provide a lock in which means is provided that has a triple function in that it prevents picking of the lock, this same means also being adapted to actuate the rope engaging dogs, and further act as a guide for the key.

A further object of my invention is to provide a device of the type described which is so designed that the standard keys now used by the mail clerks in unlocking the padlocks used in connection with the mail bags may be used in the present lock.

A further object of my invention is to provide a device of the type described in which a lug is provided with notches for permitting only a certain key having projections corresponding with the notches, to be used in the lock. The lug is strong and durable and may have different notches cut therein whereby any number of locks may be provided, each being opened by a different key.

A further object of my invention is to provide a device of the type described which is simple in construction, durable, and efficient for the purpose intended, and which is not likely to get out of order easily.

Other objects and advantages will appear in the following specification, and the novel features of the invention will appear in the appended claims.

My invention is illustrated in the accompanying drawings forming part of this application, in which—

Figure 1 is a top plan view of the device, Figure 2 is a section along the line 2—2 of Figure 1,

Figure 3 is a side elevation of the device,

Figure 4 is a section along the line 4—4 of Figure 2, and

Figure 5 is a section along the line 5—5 of Figure 2.

In carrying out my invention I provide a lock which comprises two castings A and B that are adapted to be connected to each other by connecting means such as pins or the like, so as to form a passageway through which the ropes 2 of the mail bag (not shown) are adapted to be passed. The ropes 2 are adapted to pass through an opening 3 in the lock and then around a rope engaging means 4 over rope engaging dogs 5, thence through a passageway 6 formed by a partition 7, and then out through an opening 8.

I will first describe how the rope engaging dogs 5 are adapted to bind the ropes 2 against the rope engaging means such as pins 4, whereby a movement of the ropes in the direction of the arrow, as shown in Figure 2 is prevented. The dogs 5 are spring pressed by means of springs 9 and are adapted to swing so as to force the ropes up against the pins 4. It should be noted that there are two dogs provided and that each of the dogs has a groove 10 through which the rope that it engages is adapted to pass. The dogs are serrated at 11 and this serrated portion is adapted to engage with the rope when the dogs are swung so as to bind the rope against the pin 4. I have found that it is cheaper to cast the pins 4 with the parts A and B, but it is obvious that the pins may be separated from the casting and be secured thereto. The pins 4 are also serrated at 12 and engage with the rope when the rope is moved thereagainst by means of a dog 5. The dogs 5 are rotatably mounted on a stub shaft 13 which in turn is carried by the lock.

The means for swinging the dogs 5 so as to disengage the dogs from the ropes comprises a U-shaped sleeve 14 which has a disc-shaped end 15, (see Figures 4 and 5) that is rotatably mounted upon the key receiving pin 16. The key is shown by the dotted lines in Figure 5 and in the present instance has a bore 17 therein which receives the pin 16. If it is desired to use a solid key, the pin 16 could be done away with. The wall 18 of the casting B is provided with an opening 19 through which the semi-circular portion 20 of the sleeve 14 extends. The semi-circular portion 20 acts as a bearing for the sleeve 14 and permits the

sleeve to be readily rotated in the opening and about the pin 16. The opening 19 has a recess 21 therein which is adapted to receive the tumbler engaging part 22 of the key 23.

It will be noted from Figures 2 and 4 that the sleeve 14 has a projection 24 that is adapted to engage with the dogs 5 to swing the latter into inoperative position. 10 The pin 25 limits the movement of the sleeve 14. It will further be noted from Figure 2 that the sleeve is normally held as shown in this figure by means of a retaining means such as a leaf spring 26. In the present 15 instance the spring 26 is provided with an indentation 27 that receives the projection 24. The spring has to be flexed in order to permit the sleeve 14 to be rotated. The spring 26 is passed around a pin 28 and has its end 29 secured beneath a lug 30 which is carried by the casting A. A second lug 31, 20 (see Figure 4) is carried by the casting B and bears against the end of the lug 30 so as to prevent movement of the end 29 with 25 respect to the lug. The end 29 is bent upwardly so as to prevent longitudinal movement of the spring 26.

In Figure 2 I have shown a lug 32 which 30 is carried by the casing A and which has its free end cut in the manner shown at 33 (see Figure 5). The cuts on the portion 22 of the key must correspond with the cuts by the lug 32 in order for the key to pass by the lug and to actuate the sleeve 14. As 35 shown in Figure 3 the lug 32 is positioned adjacent to the recess 21 and thus prevents the key from rotation if the key is not provided with the desired cuts. The lug 32 not only prevents the key from rotation if it is 40 not the right one, but also bears against the sleeve 14 and stops the sleeve from rotating in a counter clock-wise direction when looking at Figure 2.

The sleeve 14 is also provided with an 45 extended portion 34 that protects the dogs 5 and prevents a person from picking the lock. It will be noted from Figure 5 that the projection 34 is disposed in the casting A and that the projection is cut away at 50 so as to permit the sleeve to pass the lug 32. It will therefore be seen that the sleeve 14 has a triple function in that it prevents access to the dogs 5 whereby the dogs can only be moved by a certain key, it acts as 55 a guide for the key 23, and also as a dog actuating means. The projection 22 of the key is not large enough to engage with both dogs. Therefore it is necessary to provide a projection 24 on the sleeve 14. This projection engages with both dogs simultaneously and swings the dogs into inoperative position. Furthermore, the projection 24 engaging with the dogs instead of the key engaging with the dogs as is the case in 60 my co-pending application provides a con-

struction which gives a longer life to the key. A still further advantage in this construction lies in the fact that the standard mail bag key may be used with this lock.

From the foregoing description of the 70 various parts of the device, the operation thereof may be readily understood. A partition 35 extends from the end of the partition 6 to a point adjacent to the opening 3 and provides a passageway for each of the 75 ropes 2. It will be noted from Figure 2 that the ropes 2 may be pulled in a direction reverse to that shown by the arrow and in doing so the ropes will merely swing the dogs 5 against the tension of the springs 9. 80 As soon, however, as the ropes are pulled in the direction shown by the arrow in Figure 2, the springs 9 will cause the dogs 5 to swing so as to clamp the ropes against the serrated portions 12 of the pins 4. The 85 dogs in swinging will also bring the serrated portions 11 in engagement with the ropes 2. In this way the lock provides a novel means for permitting the ropes to be tightened at any time so as to close up the opening in 90 the mail sack but at the same time prevent the ropes from being moved in the reverse direction.

When it is desired to release the ropes 2 from the lock, the key is inserted in the 95 opening 19 and is turned so as to rotate the sleeve 14 and cause the sleeve to swing the dogs 5 into inoperative position. As heretofore stated, the lug 32 prevents any rotation of the key unless the key is the one to 100 be used. The spring 26 normally holds the sleeve 14 in the position shown in Figure 2 and it will therefore be seen that the sleeve cannot rotate into a position to obstruct the recess 21. The device is extremely 105 simple in construction and has been designed to be manufactured at a slight cost. Figure 3 shows the approximate size of the device while Figures 1, 2, 4, and 5 have been enlarged so as to clearly illustrate the construction and operation of the device. It 110 will therefore be seen that the device is compact in structure and occupies no more room than does the standard clamp now employed on mail bags. If desired, the top of the device may be provided with a channel 36 in 115 which a destination card may be inserted.

The partition 50 is disposed at right angles to the partition 7 and extends from the inner end of the partition 7 to the opening 3. The partition 50 separates the dogs 5 and also provides means for guiding the ropes over the dogs and for preventing the ropes from becoming twisted while in the lock.

I claim:

1. A mail bag lock comprising a casing, for receiving ropes, means for engaging with the ropes to permit movement of the ropes in only one direction, and key actuated means 130

for moving said rope engaging means into inoperative position, said key actuated means preventing access to said rope engaging means, thus preventing the lock from being 5 picked.

2. A mail bag lock comprising a casing for receiving ropes, means for engaging with the ropes to permit movement of the ropes in only one direction, and key actuated means 10 for moving said rope engaging means into inoperative position, said key actuated means preventing access to said rope engaging means, thus preventing the lock from being picked, said key actuated means also 15 acting as a guide for the key.

3. In a mail bag lock, rope engaging means, and a key actuated means for moving said rope engaging means into inoperative position and for holding said means 20 against return movement, said key actuated means preventing access to said rope engaging means, thus preventing the lock from being picked.

4. In a mail bag lock, rope engaging

means, and a key actuated means for moving 25 said rope engaging means into inoperative position, and for holding said means against return movement, said key actuated means also acting as a guide for the key.

5. In a mail bag lock, rope engaging 30 means, and a key actuated means for moving said rope engaging means into inoperative position, and for holding said means against return movement, said key actuated means preventing access to said rope engaging 35 means, thus preventing the lock from being picked, said key actuated means also acting as a guide for the key.

6. A mail bag lock comprising a casing having a key receiving opening therein, said 40 casing being adapted to receive ropes, means for engaging with the ropes to permit movement of the ropes in one direction, and key actuated means for moving said rope engaging means into inoperative position, and 45 means for yieldingly holding said key actuated means in alignment with said opening.

ROBERT LOWE SHANNON.
